(57) **CLAIM**

The ornamental design for a vacuum cleaner floor tool as shown and described.

DESCRIPTION

FIG. 1 is a perspective view of a vacuum cleaner floor tool according to the new design.

FIG. 2 is a front view thereof.

FIG. 3 is a rear view thereof.

FIG. 4 is a left-side view thereof.

FIG. 5 is a right-side view thereof.

FIG. 6 is a top view thereof; and,

FIG. 7 is bottom view thereof.

In these drawings, the solid lines illustrate the claimed ornamental design, whereas broken lines illustrate unclaimed subject matter and form no part of the claimed design.

1 Claim, 6 Drawing Sheets
